(57) **CLAIM**

The ornamental design for a fresh cut flower container, as shown and described.

DESCRIPTION

FIG. 1 is an isometric view of a fresh cut flower container in accordance with the invention;

FIG. 2 is a front elevational view of the fresh cut flower container of FIG. 1 and also represents an identical rear elevational view;

FIG. 3 is a right side elevational view of the fresh cut flower container;

FIG. 4 is a left side elevational view of the container;

FIG. 5 is a top plan view of the fresh cut flower container and also represents an identical bottom plan view; and,

FIG. 6 is an isometric view similar to FIG. 1, but showing the container open containing exemplary flowers shown in broken line for illustration purposes only.
